UNITED STATES PATENT OFFICE.

PHILLIP HIEN, OF CHICAGO, ILLINOIS.

FRICITION-SPRING.

SPECIFICATION forming part of Letters Patent No. 715,069, dated December 2, 1902.

Application filed September 2, 1902. Serial No. 121,756. (No model.)

To all whom it may concern:

Be it known that I, PHILLIP HIEN, a citizen of the United States, residing at Chicago, county of Cook, State of Illinois, have invented a certain new and useful Improvement 5 in Friction-Springs; and I declare the following to be a full, clear, and exact description of the invention, such as will enable others skilled in the art to which it pertains to make and use the same, reference being had to the accompanying drawings, which form a part of this specification.

My invention relates in general to apparatus for yieldingly resisting a strain or for 15 gradually absorbing a shock due, for instance, to the pull or push exerted upon the draw-bar of a car incident to the starting or stopping of a train.

A comparatively limited relative movement 20 between the draw-bar and draft-timbers of a car is permitted, and in order that the sudden shocks in pulling and buffing may be absorbed or gradually transmitted from the coupler to the car-frame it is necessary that 25 apparatus should be interposed between the draw-bar and draft-timbers of a car capable of exerting a great resistance while its members are being relatively moved the available longitudinal distance. Heretofore apparatus 30 for the purpose mentioned has comprised springs or friction-surfaces or a combination of springs and friction-surfaces, the arrangement being such that a sudden pull or push upon the draw-bar is dissipated or gradually 35 communicated to the draft-timbers of a car through compressing interposed springs or relatively moving the friction devices. In order to secure a combined spring and frictional resistance, it has previously been necessary, so far as I am aware, to employ frictional devices separate from and in addition 40 to a spring or springs.

The primary object of my invention is to provide in an apparatus for transforming a 45 sudden to a gradual relative movement between adjacent parts a plurality of elements capable when subjected to compression of individually exerting a gradually-yielding limited spring resistance and simultaneously 50 generating a frictional resistance.

A further object of my invention is to provide in an apparatus of the character re-

ferred to a series of resilient elements capable of first exerting a torsional resistance when subjected to compression and subsequently exerting a combined frictional and limited spring resistance by the relative movement between adjacent elements. 55

A still further object of my invention is to provide a device of the character referred to 60 comprising friction spring-rings having stops located adjacent to the individual rings to limit the tension to which each ring may be subjected, thereby insuring an even distribution of spring resistance to the several 65 rings, so as to prevent the breaking of any ring by its assuming a part of the total spring resistance greater than its resilient capacity.

My invention has for its final object the 70 production of an apparatus for resisting or absorbing a sudden blow or shock, which will be simple in construction, inexpensive in manufacture, and efficient in operation.

The embodiment of my invention herein 75 disclosed consists, generally described, in a plurality of friction spring-rings arranged in pairs, each pair consisting in a compressible ring supported upon an interior core and an expansible ring surrounding and engaging the 80 compressible ring and stops for limiting the expansion of each outside ring, such stops being shown in the form of circular radial flanges supported by the sections of the interior core and projecting outwardly between the several 85 pairs of rings.

My invention will be more fully described hereinafter with reference to the accompanying drawings, in which the same is illustrated as embodied in a convenient and practical form, and in which— 90

Figure 1 is a plan view of my invention, the rings being shown in the distended condition which they assume when not subjected to compression; Fig. 2, a central sectional 95 view on line 2 2, Fig. 1, showing the invention under sufficient compression to remove the normal camber of the rings; Fig. 3, a view similar to Fig. 2, showing the position of the parts when subjected to sufficient compression to completely close the rings upon each other; Fig. 4, a plan edge view of one of the expansible rings, and Fig. 5 a plan edge view of one of the compressible rings. 100

Similar reference characters are used in the several figures of the drawings to designate similar parts.

Reference characters A' and A² indicate 5 followers, between which are located spring friction-rings arranged in pairs, each pair comprising a compressible and expansible ring. The follower A' is provided with a hollow cylindrical projection A³, while the follower A² is provided with a hollow cylindrical projection A⁴ similar to the projection A³ on the follower A', toward which it extends. Supported upon the projections A³ and A⁴ is a core for supporting the friction spring-rings. In order to permit the movement of the followers toward each other, the core must yield longitudinally, and hence the same is constructed in a plurality of telescopic sections. The end section D' of the core is provided with a circular flange e', which loosely surrounds the projection A³ on the follower A', and thereby supports the section D' of the core. D² indicates the other end section of the core, which is supported upon the follower A² by means of a circular flange e², which loosely surrounds the projection A⁴ on the follower.

D indicates the central section of the core, which is supported upon the end sections D' and D² by means of oppositely-projecting circular flanges e³ and e⁴, which loosely surround circular flanges d' and d², formed on the end sections of the follower and extending toward each other. The exterior diameters of the collars d' and d² is less than the exterior diameter of the collars e³ and e⁴, so as to permit the exterior diameter of the circular flanges e³ and e⁴ to be the same as that of the flanges e' and e². The section D' of the core is provided with a radially-projecting flange E', extending from a point intermediate of the flanges d' and e'. A similar radially-projecting flange E² is supported by the section D² of the core. The central section D of the core is surrounded by and supports a radially-projecting flange E, which projects from a point intermediate of the flanges e³ and e⁴. Open compressible spring-rings C' and C² surround and are supported by the flanges e' and e², respectively, while similar compressible spring-rings C³ and C⁴ surround and are supported by the flanges e³ and e⁴, respectively. The exterior surfaces of the rings C' and C³ diverge toward the flanges E' and E, while the exterior surfaces of C² and C⁴ diverge toward the flanges E² and E. An open expansible spring-ring B' surrounds the compressible ring C' and engages an annular seat a', formed on the inner surface of the follower A'. An expansible spring-ring A² surrounds the compressible spring-ring C² and engages an annular seat a², formed on the inner surface of the follower A². B³ and B⁴ indicate expansible spring-rings which surround the compressible spring-rings C³ and C⁴ and engage the inner faces of the

flanges E' and E², respectively. Each of the expansible spring-rings is provided with an inclined interior friction-surface corresponding as to the angle of inclination to the inclined exterior friction-surface of the coöperating compressible spring-ring. The inner surfaces of the compressible rings are preferably inclined slightly in the same direction as the inclination of their exterior surfaces, thereby decreasing the thickness of the material of which the rings are formed at the vertical surfaces toward which the inclined surfaces diverge. The exterior surfaces of the expansible rings are also inclined similarly to the inclination of their interior surfaces, but at a less angle of inclination, as clearly shown in Figs. 2 and 3 of the drawings. By thus tapering the exterior surfaces of the expansible rings and the interior surfaces of the compressible rings the distribution of metal in the rings is such as to render the same capable of more uniformly exerting a resistance throughout every portion of their cross-sections. Both the compressible and expansible rings are preferably slightly spirally disposed or cambered, as clearly shown in Figs. 1, 4, and 5. A rod A, provided with a head and nut, serves to limit the movement of the followers apart.

The operation of the embodiment of my invention above described is as follows: When the followers A' and A² are moved toward each other—due, for instance, to the relative movement between a draw-bar and the draft-timbers of a car—the rings are forced together, thereby removing the camber or slightly-spiral twist. A continuation of the movement of the followers toward each other compresses the end compressible rings C' and C² through the engagement with them of the exterior-expansible rings B' and B². The end expansible rings B' and B² are then expanded until they engage the outer vertical faces of the flanges E' and E², which serve as stops to limit the expansion of the rings B' and B². A further movement of the followers toward each other causes the exterior rings B' and B² to force the flanges E' and E² toward each other, thereby moving the expansible rings B³ and B⁴ toward the central flange E. The movement of the rings B³ and B⁴ first compresses the inner rings C³ and C⁴, which in turn serve to expand the outside rings through the engaged inclined frictional surfaces. When the inner vertical edges of the rings B³ and B⁴ engage the vertical faces of the flange E, they cannot be expanded further, such flange thereby serving as a stop to limit the expansion of these rings.

It is evident from the above description that the resistance is first afforded by the camber or spiral twist of the rings, and such resistance may be sufficient to absorb the strain occurring during the ordinary running of a train, so that the expansion and contraction of the rings and the consequent frictional resistance are only brought into action when a

sudden or violent shock occurs, as in the starting or stopping of a train. When sufficient force is exerted upon the followers, the inner rings C' and C² afford spring resistance 5 and also frictional resistance through the relative movement between their inclined surfaces and the inclined surfaces on the surrounding expandible rings B' and B². A frictional resistance is also produced through 10 the engagement of the vertical surfaces of the compressible rings C' and C² with the outer vertical surfaces of the flanges E' and E². The expansion of the end rings B' and B² produces spring resistance and also frictional resistance through the engagement 15 of their inclined surfaces with the inclined surfaces of the inner rings and also through the engagement of their vertical edges with the adjacent surfaces of the followers and flanges E' and E². In a similar manner 20 the inner compressible rings C³ and C⁴ and the inner expandible rings B³ and B⁴ produce spring resistance when they are compressed and expanded and also frictional resistance 25 through their engaged inclined surfaces and also through the engagement of their vertical edges with the vertical faces of the flanges E, E', and E². The telescopic connections between the followers and the sections 30 of the core permit the followers to approach each other sufficiently to bring into action in the manner above described the several pairs of compressible and expandible rings. The location of the radial flanges E, 35 E', and E² between the pairs of rings limits the expansion of the exterior rings and insures a distribution of the resistance throughout the several rings and avoids sufficient expansion of any one ring to break the same. 40 When the force which has moved the followers together is discontinued, the tension of the rings effects the return of the parts of the apparatus to their normal positions through the inclined engaged surfaces and through 45 the camber in the rings. If desired, the several pairs of springs may be arranged to act serially, either by varying the angle of inclination of the coöperating friction-surfaces of the pairs of rings or by varying the thickness 50 of the rings.

It is apparent that my invention is adapted for a variety of uses in addition to that of serving as a draw-bar and buffing apparatus. My invention may, in fact, be used wherever 55 it is desired to absorb a violent shock or blow or to transform a violent or sudden relative movement between the coöperating parts to a gradual relative movement or to sustain a heavy load. 60 From the foregoing description it will be observed that I have invented an apparatus for resisting a strain or for dissipating a shock composed of a series of elements capable of affording frictional as well as spring resistance, thereby avoiding the employment of 65 friction devices separate from springs in or-

der to attain a combined frictional and spring resistance.

While I have described more or less precisely the details of construction, I do not 70 wish to be understood as limiting myself thereto, as I contemplate changes in form, the proportion of parts, and the substitution of equivalents, as circumstances may suggest or render expedient, without departing from the 75 spirit of my invention. I do not, however, claim the invention herein disclosed generically, inasmuch as the generic invention common to this application and to my prior application, Serial No. 116,187, filed July 19, 80 1902, is claimed in said prior application, nor do I claim herein the generic invention disclosed in common by this application and by my prior application, Serial No. 117,244, filed July 28, 1902, as such common invention is 85 claimed in said prior application, Serial No. 117,244; but I do claim in this application only the features of construction not disclosed in either of my said prior applications.

Having now fully described my invention, 90 what I claim as new, and desire to secure by Letters Patent, is—

1. The combination with a series of resilient elements having inclined frictional surfaces, the surfaces of adjacent elements adapted 95 when said series of elements are subjected to compression to be relatively moved through the engagement with each other, of means for limiting the tension to which each element may be subjected. 100

2. The combination with a series of resilient rings having inclined frictional surfaces adapted when said series of rings are compressed to be relatively moved thereby placing said rings under tension, of means for 105 limiting the tension to which each ring may be subjected.

3. The combination with an expandible spring-ring of a compressible spring-ring, said rings having inclined engaging frictional surfaces, of means for limiting the relative movement of said rings when they are subjected to compression. 110

4. The combination with a series of spirally-disposed expandible spring-rings having inclined frictional surfaces of a series of spirally-disposed compressible spring-rings having frictional surfaces engaged by the surfaces of the expandible rings when the series is subjected to compression, of means for limiting the tension to which each ring may be subjected. 115

5. The combination with a series of expandible spring-rings having inclined frictional surfaces of a series of compressible spring-rings 120 having inclined frictional surfaces coöperating with the surfaces of the expandible rings, and means for limiting the expansion of each individual expansion-ring. 125

6. The combination with an expandible spirally-disposed spring-ring having an inclined frictional surface, of a spirally-disposed com- 130

pressible spring-ring having an inclined frictional surface coöperating with the surface of the expansible ring, and means for limiting the relative movement of said rings when 5 they are subjected to compression.

7. The combination with a series of spring-rings having inclined frictional surfaces, of a series of inclined frictional surfaces engaged by the inclined frictional surfaces of said 10 rings, and means for limiting the tension to which each individual ring may be subjected when the series of rings are compressed.

8. The combination with a series of resilient elements having inclined frictional surfaces, of a core surrounded by and supporting said elements, and radial projections secured to said core to limit the movement of individual elements when the series is subjected to compression.

20 9. The combination with followers, of a telescopic core supported by said followers, a series of expansible spring-rings having inclined frictional surfaces, compressible spring-rings surrounding said core and supported thereby, and having inclined frictional surfaces coöperating with the frictional surfaces of the expansible rings, and radial flanges supported by said core, one flange extending adjacent to each expansible ring to limit the tension which may be imposed upon it.

10. In an apparatus of the character described, the combination with a plurality of pairs of spring-rings, each pair comprising 35 an expansible and a compressible ring, having inclined coöperating frictional surfaces, of stops engaged by each pair of rings to limit the tension which may be imposed upon the same when the apparatus is subjected to 40 compression.

11. In an apparatus of the character described, an open spring-ring having inclined exterior and interior surfaces one of which is adapted to coöperate with a similarly-inclined surface to impart tension to the ring.

45 12. In an apparatus of the character described, a spirally-disposed frictional spring-ring having inclined exterior and interior surfaces one of which is adapted to coöperate 50 with a similarly-inclined surface to remove

the spiral twist from, and impart tension to the ring.

13. In a device of the character described, the combination with a series of expansible resilient elements, of a series of non-resilient 55 elements supported adjacent to said expansible elements, said expansible resilient elements and said non-resilient elements having engaging frictional surfaces at an angle to the axis of the resilient elements whereby 60 when said resilient elements are expanded the frictional surfaces thereon are moved relatively to the engaged frictional surfaces on said non-resilient elements.

14. In a device of the character described, 65 the combination with a series of expansible spring-rings, of a series of plates supported adjacent to said rings, said rings and plates having engaging frictional surfaces whereby when said rings are expanded the frictional 70 surfaces thereon are moved relatively to the engaged frictional surfaces on said plates.

15. In a device of the character described, the combination with a series of expansible spring-rings, of a series of plates, a core surrounded by and supporting said rings and plates, said rings and said plates having engaging frictional surfaces whereby when the rings are expanded the said frictional surfaces thereon are moved relatively to the engaged frictional surfaces on said plates. 75

16. In a device of the character described, the combination of a series of expansible spring-rings having inclined frictional surfaces, of a series of compressible spring-rings 85 having inclined frictional surfaces engaging the inclined frictional surfaces of the expansible rings, a core surrounded by and supporting said rings, and radially-projecting plates carried by said core, said compressible 90 and expansible rings having frictional surfaces adapted to engage and move relatively to said plates when the rings are respectively compressed and expanded.

In testimony whereof I sign this specification in the presence of two witnesses.

PHILLIP HIEN.
